(57) **CLAIM**

I claim the ornamental design for a bottle, as shown and described.

DESCRIPTION

FIG. 1 is a front-left, top perspective view of a bottle in accordance with my new design;

FIG. 2 is a front view thereof;

FIG. 3 is a rear view thereof;

FIG. 4 is a right view thereof, the left view being omitted as a mirror image of the right view of FIG. 4;

FIG. 5 is a top view thereof; and,

FIG. 6 is a bottom view thereof.

The broken lines depict portions of the bottle that form no part of the claimed design.
